Patented Oct. 9, 1973

228,543

COMPARTMENTED PACKAGING TRAY

George E. Jansen, Cedar Grove, N.J., assignor to The Pantasote Company of New York, Inc., New York, N.Y.

Filed Sept. 20, 1971, Ser. No. 182,286

Term of patent 14 years

Int. Cl. D9—03

U.S. Cl. D9—187

FIG. 1

FIG. 3

FIG. 2

FIG. 4

FIG. 1 is a top perspective view of a compartmented packaging tray embodying my new design;

FIG. 2 is a side elevational view;

FIG. 3 is an end elevational view looking in the direction of the arrow 3—3 of FIG. 1; and

FIG. 4 is a sectional view taken on the line 4—4 of FIG. 2.

I claim:

The ornamental design for a compartmented packaging tray, as shown.
